UNITED STATES PATENT OFFICE.

ANDREW L. RIKER, OF BRIDGEPORT, CONNECTICUT, ASSIGNOR TO THE LOCOMOBILE COMPANY OF AMERICA, OF NEW YORK, N. Y., A CORPORATION OF WEST VIRGINIA.

REGULATING MEANS FOR INTERNAL-COMBUSTION ENGINES.

1,149,597.

Specification of Letters Patent. Patented Aug. 10, 1915.

Application filed June 8, 1903. Serial No. 160,470.

To all whom it may concern:

Be it known that I, ANDREW L. RIKER, a citizen of the United States, residing at Bridgeport, in the county of Fairfield and

5 State of Connecticut, have invented an Improvement in Regulating Means for Internal-Combustion Engines, of which the following description, in connection with the accompanying drawings, is a specification, 10 like letters on the drawings representing like parts.

My invention relates to motor vehicles of the type employing what are known as internal combustion engines,—that is, engines 15 wherein a mixture of fuel and air is admitted to the engine cylinder and there ignited in suitable manner, as by an electric spark, to furnish the operating power for the engine and the vehicle.

20 While my invention is particularly adapted for motor vehicles in connection with which I shall here illustrate and describe the same, obviously my invention may be used for furnishing power for any other 25 purpose, if desired and adapted therefor.

My present invention, among other things, aims to provide improved means for throttling the combustible mixture for the engine, either automatically by the governing device, 30 or manually, as may be desired, whereby a simpler, more efficient and otherwise improved result is obtained.

The nature of my invention will be more 35 clearly understood from a description and illustration of a specific embodiment thereof, such as illustrated in the accompanying drawings, wherein,—

Figure 1, in vertical section, illustrates the device for mixing and controlling the 40 supply of combustible for the engine; Fig. 2, a horizontal section of a part thereof on the dotted line 2—2; Fig. 3, a sectional detail illustrating the speed responsive governing device; Fig. 4, a diagrammatic view 45 illustrating the connection between the regulating device and the speed responsive governor, as well as with the manually controlled handle; Fig. 5, a detail showing the throttle arms in side elevation, partially 50 broken out; Fig. 6, a sectional detail showing one form of treadle or clutch controlled throttling valve; Figs. 7 and 8, details illustrating the valve walls and their parts developed; Fig. 9, a similar view showing the

two walls one behind the other; and, Fig. 55 10, a view illustrating, in side elevation a motor vehicle equipped with devices embodying my invention.

In the embodiment of my invention selected for illustration herein and shown in 60 the drawings, referring first to Figs. 1 to 3, inclusive, the fuel and air mixing and controlling device is indicated generally by the letter M. The fuel supply pipe, h, leading from the supply tank or reservoir, as H, 65 Fig. 10, under the seat of the vehicle, enters at the lower left-hand portion of Fig. 1, where it is suitably connected with a separator, m, depending from the principal casting, m', in which the various working parts 70 are preferably arranged. The bottom of the separator, m, is closed by a plug, m², which is provided with a vertical tubular extension m³, flanged outwardly at its top to fit closely the bore of the separator, thus to 75 compel fuel from the pipe, h, to pass through the side openings, m⁴, in the said extension to the interior thereof. Any water which may be mixed with the fuel separates 80 therefrom in the separator, m, and may be drawn off through a cock, m⁵, in the bottom thereof. The fuel, after passing through the separator, m, rises through the opening, m⁶, into the float chamber, m⁷, formed within the casting, m'. The entrance opening 85 m⁶, is controlled preferably by a ball valve, m⁸, on the lower end of a valve stem, m⁹, which rises through the float chamber and has threaded upon its upper end a stop 90 guide, m¹⁰, which guides the valve stem in its vertical movements. Loosely surrounding the valve stem, m⁹, in the float chamber, is the float, m¹², which rises with the fuel in the said chamber and when the fuel reaches the proper level therein, said float contacting with the bottom of the stop guide, m¹⁰, on the valve stem referred to, will lift the valve stem and its valve to close the valve opening, m⁶ and cut off further admission of 95 fuel. The level of fuel in the float chamber 100 thus maintained by the float, may be regulated at will by threaded adjustment of the stop guide on the valve stem, since the position of the said stop guide on the said valve stem determines the level at which the float 105 will lift the valve to cut off further admission of fuel. The protruding end of the valve stem, m⁹, above the float chamber, is

shown inclosed in an inverted cup, m^{13} , perforated at its top to receive the vertically sliding starting device, m^{14} , normally retained in its elevated position by the spring 5 m^{15} . By depressing this starting device, the valve stem may be manually depressed, to open the valve, to admit additional fuel to the float chamber for starting the engine, as will be hereinafter fully described.

10 At or near the bottom of the float chamber, m^7 , is an outlet passage, m^{16} , which communicates with an annular chamber, n , surrounding the atomizing nozzle, n' , screwed into the bottom of the mixing chamber N.

15 This atomizing nozzle, n' , has a vertical axial passage, n^2 , with which the outlet passage, m^{16} , communicates through one or more side openings, n^3 . The atomizing nozzle, n' , is provided with an exteriorly tapered upper end, which is arranged within a central aperture, n^4 , in the lower end of a throttle cylinder or cylindrical throttle, n^5 , arranged within the mixing chamber N, and adapted to be rotated therein by means of 20 a stem, n^6 . Within the cylindrical throttle, n^5 , and immediately above the nozzle, n' , is an opposed deflecting cone, n^8 . The general conical surface of this cone, n^8 , is preferably stepped, as shown, thereby more effectually to dissipate and break up the mixture projected against it. The mixing chamber, N, near its lower end, is provided with an air inlet, n^9 , and near its upper end, is provided with an outlet n^{10} , and immediately 25 opposite the opening, n^{10} , the cylindrical throttle n^5 , is provided with a corresponding opening, n^{11} , adapted when in proper rotative position to register with the said opening, n^{10} . Said throttle also has, at 30 its opposite side, an auxiliary air inlet opening, n^{12} , to be referred to. Rotation of the cylindrical throttle, n^5 , will thus open and close the opening n^{10} , in the side of the mixing chamber, but as the bottom of the cylindrical throttle is above the bottom of the air inlet opening, n^9 , the admission of air is never cut off. The opening n^{10} , at the upper end of the mixing chamber N, see Figs. 1 and 2, is suitably connected by a pipe, n^{13} , 35 with the engine, E, Fig. 10, whereby the movements of the pistons therein, in a manner well understood by those conversant with the operation of internal combustion engines, will create a sufficient vacuum to draw air inward through the inlet n^9 , thence upward within the cylindrical throttle, drawing from the nozzle, n^2 , the liquid fuel which is maintained therein at a level with that of the fuel in the float chamber, m^7 , 40 which level preferably is slightly below the top of the said atomizer nozzle. This fuel is projected with considerable force against the opposing baffle cone, n^8 , which scatters and atomizes it, and causes it to be thoroughly 45 mixed with the air surrounding it, the com-

bined mixture of fuel and air passing thence outward through the opening, n^{10} , to the engine, there to perform its work. As the atomizer draws the fuel from the float chamber, m^7 , the float recedes with the level of fuel therein, and opens the valve m^8 , to admit a further supply of fuel, the action being such that in practice the float maintains the valve normally open sufficiently to insure a substantially continuous admission of fuel both to the float chamber and also to the mixing chamber N.

To start the engine, when there is no vacuum therein to draw the air and fuel from the mixing chamber, it becomes necessary to provide other means for furnishing initially the required supply of carbureted air for the first ignition. This may be accomplished in the apparatus described, by depressing the starting device, m^{14} , Fig. 1, thereby depressing the valve stem, m^9 , and opening the valve m^8 , to permit fuel gravitating from the higher level of the reservoir, H, to rise in the float chamber, m^7 , sufficiently to overflow the top of the atomizer nozzle, n' , in the chamber, N. If, now, the crankshaft of the engine be given a rotation, the movements of the pistons therein will draw air from the inlet opening, n^9 , and in contact with this fuel, thereby carbureting the air on its way to the engine, and furnishing a sufficient supply of air or combustible to set the engine in motion upon closing of the circuit leading to the sparking devices. Surrounding the throttle cylinder, n^5 , and between it and the wall of the chamber N, is an adjusting cylinder, 100, provided at one side with a port or opening, 101, to coöperate with the throttle port, n^{11} , and chamber exit, n^{10} , said adjusting cylinder at its opposite side having an auxiliary port, 102, Fig. 2, to coöperate with an auxiliary air inlet opening, 103, in the chamber N, as well as with the auxiliary throttle opening n^{12} . This adjusting cylinder, 100, has its head, 104, mounted on the tubular stem, 105, which rises through the neck of the chamber cap, N', and receives upon its upper threaded end a lock nut, 106. The chamber cap, N', is screwed into the top of the chamber, 115 N, and so is the adjusting cylinder, 100, below it, so that any tightening of the lock nut, 106, clamps the adjusting cylinder against rotative movement in and relative to the ports or openings in said chamber.

Referring to Fig. 4, the throttle stem n^6 has fast upon its upper end a lever or arm, 25, Fig. 5, to the end of which is jointed a return lever, 26. To an intermediate point in the return lever, 26, is connected a rod, 27, which leads to an arm, 28, on the lower end of a rod, p^{29} , journaled in bearings at the side of the steering post, p^{30} , and provided at its upper end with a handle, p^{31} , shown in dotted lines, Fig. 4, by which said 130

rod may be rotated in one or the other direction. To the end of this same return lever, 26, is connected a rod, 107, which leads to the arm, p^{19} , fulcrumed at p^{20} and having its inner end resting in the circumferential groove of the slideable collar, p^{16} , Fig. 3, of a speed responsive governing device. This governing device may be of any suitable type or construction. It is sufficient here to say that, in the governor illustrated, the circumferentially grooved collar, p^{16} , has its hub provided with an inclined or skew slot, p^{17} , which receives a pin, p^{18} , on the shaft, p^2 . When the governor weights, not shown, move away from the axis of rotation, they cause the head, p^9 , to rock relatively to the shaft p^2 , and through the pins p^{15x} , which penetrate the said collar p^{16} , cause the latter to receive corresponding rotation and as the collar is rotated, it is by its slot p^{17} and pin p^{18} moved axially of the shaft p^2 . Thus, as the speed increases and the governor weights move away from the axis of rotation, the outer end of the lever p^{19} , is moved to the right, Fig. 4, whereas if the speed decreases, the said parts will move in an opposite direction or to the left, Fig. 4. The rocking head p^9 , carries also the contact head, p^{11} , carrying the sparking contacts which coöperate with the fixed contacts or brushes p^{15} , whereby the time of sparking of the engine is controlled simultaneously with the regulation of supply of combustible mixture admitted to the engine.

control is effected by movement of the throttle with reference to the opening in the stationary adjusting cylinder. When, however, it is desired manually to vary the speed of the vehicle, irrespective of the governor controlled speed thereof, the operator, through the handle p^{31} referred to, may swing the return lever 26, in one or the other direction about the end of the rod, 107, as a fulcrum and thereby open or close the throttle ports regardless of the position of the governor and the rod, 107. If the handle, p^{31} , be moved to the right, Fig. 4, the throttle will be rotated in a direction opposite the arrow 66, Fig. 2, thereby to enlarge the opening through which the combustible mixture may pass to the engine, and it matters not in what position the throttle may be when the handle p^{31} is about to be moved, any movement of the said handle to the right, Fig. 4, will turn the throttle in a direction opposite the arrow 66, and enlarge the port opening to admit increased supply of combustible to the engine to cause the latter to speed up. On the other hand, if the said handle, p^{31} , be moved to the left, Fig. 4, the throttle n^5 will be turned in the direction of the arrow 66 and will reduce the area of the port opening n^{11} , below that fixed by the governor. For instance, as shown in Fig. 2, rotation of the throttle in the direction of the arrow 66, will reduce that opening, and assuming the governor position of the throttle to be one almost cutting off the passage n^{10} ,

Referring now to Fig. 2, the openings 101, 102, in the outer or manually positioned adjusting cylinder n^5 , are shown in their normal or running position, which are determined by experience, in the best positions for the particular engine and the work to be performed. The inner, governor-controlled throttle, n^5 , has its opening, n^{11} , overlapping the opening, 101, in the outer, adjusting cylinder; so that as shown, there is free exit of the combustible from within the throttle, to the passage, n^{10} , thence to the engine. As the speed of the engine increases, the governor responds through the connections described, moves the rod 107, Fig. 4, to the right, and swings the return lever, 26, about the end of the rod 27 as a fulcrum, and thereby swings the arm, 25, to turn the throttle, n^5 , in the direction of the arrow, 66, Fig. 2, more or less to cut off the supply of combustible to the engine, according to the increase in speed of the engine; and if the speed of the engine rises sufficiently, said throttle will move far enough to cause the wall of its opening, n^{11} , to lap the wall of the opening, 101, in the outer adjusting cylinder, and thereby completely cut off the supply of mixture to the engine. Thus, in the ordinary running of the vehicle, the governor movement of the outer throttle in a direction opposite the arrow 66, will open the supply of combustible to the engine. Thus, at any time, whether the vehicle be running fast or slow, and whether the governor is calling for a maximum or minimum supply of mixture for the engine, the operator by the handle p^{31} , may remove the throttle from the control of the governor and vary the opening either above or below that determined by the governor. If this adjusting cylinder, when thus manually moved, be permitted to remain in its new position, the governor controlled speed of the vehicle is correspondingly changed, since the governor thus operates relative to a new position of the adjusting cylinder. The leading vertical or side walls of the throttle ports n^{11} and n^{12} are preferably made inclined, as best indicated in Figs. 8 and 9, in order that a more gradual opening and closing may be had. If it be found that in either extreme position of the throttle, the port openings are too large or too small, the error may be corrected by adjustment of the adjusting cylinder, 100, in the required direction, to shift the positions of its ports 101 and 102.

In Fig. 10, in the vehicle there shown, the wheels are indicated at a , b for carrying in

In Fig. 10, in the vehicle there shown, the wheels are indicated at *a*, *b* for carrying in 130

usual manner the spring supported frame *c* with the body *C'* mounted thereon and indicated in dotted lines. The engine *E* mounted upon said frame *c* operates through a usual transmission gear at *T*, to drive the jackshaft *f*, thence to the hubs of the rear wheels, *b*, this figure typifying merely a vehicle to which my invention is peculiarly applicable. The transmission gear *T*, is 10 operated from the engine *E*, through a usual clutch *e³*, which is under the control of the treadle *f¹⁶*. When the vehicle is to be started, the treadle shown is released and permitted to rise to throw in the clutch and 15 to start the vehicle, the treadle being depressed to throw out the clutch. As here shown, also, the brake *g³¹*, has its operating lever *g³²*, connected by a rod, *g³³*, with the treadle *f¹⁶*, so that whenever said treadle is 20 depressed to release the clutch, the brake is by the same movement applied, proportionately to the degree of depression of the treadle. Thus the clutch is thrown out and the brake set, by one and the same movement of the treadle, and the brake is released and the clutch thrown in also by one and the same, but opposite movement of said treadle. To provide against racing of the 25 engine when the clutch is temporarily or otherwise thrown out, I have connected the said treadle, *f¹⁶*, by a rod, 110, with and to operate a suitable valve, here shown as a butterfly valve, 111, Figs. 10 and 6, in the engine supply pipe, whereby when the said 30 treadle is depressed to release the clutch and apply the brake, the supply of combustible mixture to the engine is also cut off. Obviously, when the treadle is permitted to rise, to throw in the clutch and 35 release the brake, the valve, 111, is oppositely moved to again admit combustible mixture to the engine for the operation thereof. The adjustments of the various 40 connections described, may be such as to provide any required order of timing of the movements of the valve, 111, clutch and brake, so as to permit, if desired, either one to precede another or the others in its or 45 their movements. Ordinarily, the engine, 50 by the valve, 111, and the clutch will be cut out and in simultaneously, while the brake operation will follow the cutting out and precede the cutting in thereof.

My invention obviously is not restricted to 55 the use and embodiment here shown and described, but may be varied as required for various uses and adaptations within the spirit and scope of my invention.

Claims:

60 1. Regulating means for an internal combustion engine, the same comprising a rotary throttle, combined governor and manual controlling means for rotating the same therefor, and a coöperating throttle regulator arranged concentrically therewith and

arranged for independent rotary adjustment.

2. Regulating means for an internal combustion engine, the same comprising a mixing chamber provided with manually and 70 governor controlled throttling means, and air and fuel mixing means arranged within said throttling means and coöperating auxiliary air supplying means communicating with said chamber and controlled by said 75 throttling means.

3. The combination with an internal combustion engine of a gas mixing chamber, a fuel admission passage leading therefrom to the engine, throttling means for said passage, combined manual and automatic controlling means for said throttling means, 80 an auxiliary air supply means for said mixing chamber, auxiliary throttling means for said auxiliary air supply means, and means 85 for controlling said auxiliary throttling means.

4. Regulating means for an internal combustion engine, the same comprising a chamber, a rotatable throttle device in said chamber, and provided with an opening and a throttle regulating device also in said chamber and arranged concentrically within said throttle and by which to vary the throttle opening, one of said devices having an operating arm for moving it, and a plurality of 90 actuators connected therewith for independently operating it.

5. Regulating means for an internal combustion engine, the same comprising a mixing chamber provided with fuel and air mixing means, a rotatable throttle device in 100 said chamber and provided with an opening, and a throttle regulating device also in said chamber and arranged concentrically 105 with respect to said throttle and by which to vary the throttle opening, said throttle and regulating device having coöperating openings, a wall of one of said openings being inclined to the coöperating wall of the 110 other opening, and said mixing means being substantially contained and operating within one of said devices.

6. Regulating means for an internal combustion engine, the same comprising a 115 throttle, operating connections therefor, manual controlling means for said connections, governor controlling means also therefor permitting either a manually or governor similarly controlled opening and closing movement for the throttle, and adjustable, fixed throttle regulating means.

7. The combination with an internal combustion engine, of a gas mixing chamber, a fuel admission passage leading therefrom to said engine, a rotary hollow cylindrical throttle valve within said chamber and controlling said admission passage, a stem axially connected to said throttle, an arm connected to turn said stem, a speed governor 125 130

connected to said arm, and a separate controlling lever also connected to control the fuel supply independently of said governor.

8. The combination with an internal combustion engine, of a fuel supply passage leading thereto, a rotary, cylindrical throttle valve controlling the same, a supplemental air supply passage also controlled by said throttle, and a throttle regulator for varying the available area both of said supply passage and said air passage.

9. In an internal combustion engine, the combination of a mixing chamber N having a bearing for a rotary valve stem n^6 , a tubular throttle valve mounted thereon to rotate within said chamber and having an apertured end adapted to receive the nozzle of a fuel atomizer n^2 , and a baffle cone n^8 mounted upon the lower end of said valve stem in juxtaposition to said nozzle.

10. In an internal combustion engine the combination of fuel supply means, throttling means therefor provided with an actuating arm 25, a speed governor for regulating said throttling means having connecting devices including a governor connected lever p^{19} , a link 107 connected with said lever and an arm 26 pivotally connected with the latter and said actuating arm 25 and manually controlled means separately connected with said arm 26 for independently operating the same.

11. In an internal combustion engine, regulating means therefor, comprising a fuel mixer chamber N , an auxiliary air supplying chamber 103 and throttling devices intermediate the same and said mixing chamber comprising the concentrically arranged rotary throttle n^5 and throttle regulator 100 each provided with co-operating openings.

12. In an internal combustion engine, regulating means therefor, comprising a fuel mixer chamber N , an auxiliary air supplying chamber 103 and throttling devices intermediate the same and said mixing

chamber comprising the concentrically arranged rotary throttle n^5 and throttle regulator 100 each provided with co-operating openings, a wall of one of said openings being inclined.

13. The combination with an internal combustion engine, of a gas mixing chamber having a main air supply and an auxiliary air supply, a fuel passage leading therefrom to the engine, throttling means for said fuel passage, throttling means for said auxiliary air supply, and combined manually and governor controlled connections for said first mentioned throttling means each for alternately and exclusively controlling said throttling means.

14. The combination with an internal combustion engine, of a gas mixing chamber, a fuel admission passage leading therefrom to the engine, a main air supply, an auxiliary air supply, throttling means for said auxiliary air supply, manual controlling means for said throttling means, and governor controlled connections also for said throttling means, said manual controlling means and governor-controlled connections each alternately controlling the throttling means to the exclusion of the other.

15. Regulating means for an internal combustion engine the same comprising a throttle, operating connections therefor, manual controlling means for said connections, governor controlling means also therefor permitting either a manually or governor controlled opening and closing movement of the throttle and adjustable fixed regulating means for regulating both the extent of throttle opening and the supply of auxiliary air.

In testimony whereof, I have signed my name to this specification, in the presence of two subscribing witnesses.

ANDREW L. RIKER.
